DESCRIPTION

FIG. 1 is a front perspective view of the sweatshirt with
wrist-to-chest zippers, showing my new design;

FIG. 2 is the back view thereof;

FIG. 3 is a front elevational view showing a person wearing
the sweatshirt thereof; and,

FIG. 4 is a back elevational view showing a person wearing
the sweatshirt thereof.

The broken lines shown in the drawings depict stitching and
form no part of the claimed design.

The broken line showing a person wearing the sweatshirt in
FIGS. 3 and 4 is for the purpose of depicting environmental
structure and forms no part of the claimed design.

1 Claim, 4 Drawing Sheets
